(57) **CLAIM**

The ornamental design for a toothbrush holding container, as shown and described.

DESCRIPTION

FIG. 1 is an exploded front elevation view of a toothbrush holding container showing my new design, an exploded back elevation view being a mirror image thereof, an exploded right side elevation view being identical, an exploded left side elevation view being a mirror image thereof;

FIG. 2 is an exploded top plan view thereof;

FIG. 3 is an exploded bottom plan view thereof; and,

FIG. 4 is an exploded top front side perspective view thereof.

The broken line showing of toothbrush holding container is included for the purpose of illustrating portions of the "article" and forms no part of the claimed design.
